Carl P. Affulles.

UNITED STATES PATENT OFFICE.

HARRINGTON S. BARROWS, OF CLEVELAND, OHIO.

LIQUID-RECEPTACLE.

1,343,299.

Specification of Letters Patent. Patented June 15, 1920.

Application filed September 25, 1919. Serial No. 326,195.

To all whom it may concern:

Be it known that I, HARRINGTON S. BARROWS, a citizen of the United States, residing at Lee and Mayfield Roads, in the city 5 of Cleveland, county of Cuyahoga, and State of Ohio, have invented a new and useful Improvement in Liquid-Receptacles, of which the following is a specification, the principle of the invention being herein explained and the best mode in which I have 10 contemplated applying that principle, so as to distinguish it from other inventions.

My invention relates to a liquid receptacle and more particularly to a dish or container with a plurality of peculiarly related compartments each of which is intended to receive a different liquid and at least one of which is to be kept hermetically sealed by means of a detachable cover.

20 In the practice of dentistry precious metal, for example gold, must be cleaned prior to insertion into a tooth cavity and such cleaning is ordinarily effected by dipping the gold into a strong acid the fumes 25 of which are destructive. It therefore becomes necessary subsequently to neutralize any acid adhering to the gold prior to insertion into the mouth of the patient. For this purpose an alkali such as soda is employed and finally the gold is rinsed by dipping the same into water. It is desirable therefore to have the three liquids, namely, the acid, the alkali and the water, ready to hand and accordingly, a dish embodying 30 my invention is purposed to contain these three liquids. It is important that the acid compartment be kept hermetically sealed except momentarily when the gold is to be dipped therein and it is furthermore desirable 35 to have the three liquids close together to enable that the successive dipping from one to the other in the order already mentioned with a minimum of effort and loss of time prior to fitting of the gold into 40 the tooth. Moreover, it is preferable to so shape the dish that the successive dipping operations may be performed without allowing drops to fall beyond the confines of the dish until after the gold has been 45 rinsed in water.

Consonantly, the object of my invention is to provide a dish adapted to serve as part of dental equipment and to permit of ready access to a plurality of liquids including an 50 acid the fumes of which, if allowed to es-

cape, will injuriously affect metal such as that of the tools employed by a dentist or rust any other metal objects exposed thereto. A further object is to provide the acid compartment with a relatively small 60 opening adapted to be hermetically sealed as by means of a ground glass fit. Such an arrangement incidentally permits of the receptacle being held so that the bottom may be supported upon one or more fingers and the ground glass cover or stopper held in place by the thumb and so whereby the entire receptacle may be inverted to enable the soda and the water to be poured out 65 preparatory to replacement as is regularly required.

It should be understood that a receptacle embodying the features of my invention is adapted equally well to the jewelers trade and doubtless to other industrial shops in which 70 the cleansing of precious metals by means of an acid bath is regularly practised.

Adverting to the drawing:

Figure I is a top plan view of a receptacle 80 embodying my invention; the cover having been removed.

Fig. II is a vertical section on zig-zag line 85 II—II of Fig. I for the additional cover likewise shown in section and showing an interior stopper appearing in elevation.

Fig. III is a plan section on line III—III of Fig. II looking downwardly.

The receptacle, which may be composed of moldable material such as porcelain or 90 glass, comprises a bowl 1 and extending upwardly interiorly thereof is a partition 2 having three radial extensions 3, 4 and 5 respectively which together divide the bowl 1 into three substantial equi-sized compartments. Such compartments are purposed to 95 contain one an acid, the other a soda and the third water.

Owing to the destructiveness of the fumes 100 of the acid usually employed for the cleansing of precious metals, and specifically because the fumes of the acid readily attack the nickel-plated coating of instruments and thus eventually cause them to rust, it becomes desirable if not indeed necessary to 105 keep the acid hermetically sealed except during the few moments which elapse while the metal is being dipped therein. To this end, it will be observed that the acid compartment which is in part defined by the radial 110 extensions 4 and 5 is provided with an in-

tegral top 6 having an upper surface 7 depressed relative to the top of the partition 2 and also relative to the upper rim of the bowl 1. At its middle the top 6 is fashioned with a tapered hole 8 adapted to snugly receive a ground glass stopper 9. Over the receptacle including its three compartments is a cover 10.

It is clear that the stopper 9 enables the acid compartment to be hermetically sealed and thereby precludes the rusting of metal implements which might otherwise be exposed to an attack by the acid fumes. At the same time the other two compartments, which it is required to have readily accessible in order first to neutralize the acid coating and then to rinse the metal, may be constantly open and by use of my invention are in closest possible proximity thereby minimizing the physical effort and time required to perform the three dipping operations. Incidentally, such an arrangement as my receptacle provides permits of the successive dipping of the metal to be cleansed without necessitating its manual conveyance beyond the outermost confines of the receptacle prior to the last act of dipping into the water. In this manner all the dipping operations may be performed without allow-

ing destructive drops to fall outside of the receptacle during the wet transfer of the precious metal from one compartment to another. It is common practice to supply the receptacle each day with fresh soda and fresh water. My invention enables the receptacle to be grasped so that the fingers engage the bottom while the thumb engages the top of the stopper thereby enabling the receptacle to be inverted and the soda and water emptied without permitting the escape of any acid.

I claim:—

A device of the character described comprising as an integral construction a hollowed piece of vitreous material divided by upright partitions into a plurality of laterally adjacent compartments each open above but having no communication with each other, one of which includes an integral cover provided with a hole, a stopper for hermetically sealing said hole, and a cover for the entire receptacle adapted directly by itself to extend over to close all of said compartments and to inclose said stopper.

Signed by me, this 18th day of September, 1919.

H. S. BARROWS.
